ADVERTISING DEVICE

William W. Miller, Berwyn, Ill., assignor to General Outdoor Advertising Co., Inc., Chicago, Ill., a corporation of New Jersey

Application May 31, 1934, Serial No. 728,200

3 Claims. (Cl. 40—30)

This invention relates to a novel and improved advertising device and consists of the matters hereinafter described and more particularly pointed out in the appended claims.

5 The object of the invention is to provide a mechanism including a face plate upon which is made to appear, as if painted thereon, a face which is caused by the mechanism and arrangement of parts to change in coloring or character 10 by the operation of the mechanism.

In the particular embodiment of the invention shown and described herein, the face is that of a woman which is caused in the operation of the apparatus at one time to present all the brilliant 15 coloring of youth, whereas at another time the same face appears as if masked by a white film. The advantage of such a mechanism for advertising will be obvious. In this case the device is for the advertisement of a face powder. The 20 result of the use of the advertised face powder is pictorially presented by the one view, in which the bright coloring appears on the face, which is brought into sharp contrast to the view when changed and which is designed to show a result 25 of the use of other face powders.

The device is illustrated herein as erected upon the familiar advertising board with the face of exaggerated size to be visible at long distances. Its use in connection with smaller sign boards 30 will be apparent.

In the drawing:—

Figure 1 is a front face view of a signboard provided with the improved advertising device;

Figure 2 is a vertical section through the advertising device in a plane indicated by the line 35 2—2 of Figure 1;

Figure 3 is a front face view of the picture frame, which forms the front of the device and in which appears mounted the picture of the 40 face on view;

Figure 4 is a front elevation of a back plate which forms part of the apparatus; and

Figure 5 is a perspective view of an endless band mounted on vertically spaced rolls. The 45 movement of the band brings about the change in the appearance of the face of the picture.

In Figure 1 the face of a girl or woman appears in the frame with the natural coloring of youth, designed to illustrate the result of the 50 use of the powder (in this case) of the advertisement.

In Figure 3 appears the same face but in this case with the white film or mask attributed to be left by the use of other or inferior face powders.

55 Referring now to the drawing and to the em-

bodiment of the invention shown therein:— 10 indicates a signboard of familiar construction. 11 indicates the novel advertising device which, as shown herein, is embodied in and made a part of the signboard. 12 indicates a picture frame 60 forming part of the front wall of the signboard, mounted in a rabbet 13 defining a rectangular opening in said front wall. In the picture frame 12 is mounted a transparent face plate 14, preferably of glass. A back plate 16 is mounted at 65 the rear of but close to the face plate 14. This back plate is held in place by means of straps or bars 17, 17 attached in any suitable manner to the wall structure of the sign.

18 indicates a vertically disposed endless band 70 with its top and bottom loops engaged upon rolls 19, 20 suitably mounted in the walls of the signboard and with its forward lap 15 passing between the face plate 14 and the back plate 16. The bottom roll 20, as shown, is a driving roll and 75 may itself be driven in any suitable manner, as for example, by a motor 21 mounted in the base of the sign or device. The endless band 18 in this case is made of white paper or canvas and is provided with an elongated opening or window 15a. 80

On the transparent face plate 14 there is painted, printed or in other way presented, a head 14a with the unchangeable features of the picture to be depicted, as for example, the hair. Also on the said face plate are depicted eyes, eyelashes, 85 and eyebrows 22, nostrils 23 and lips 24, which likewise are features of the picture intended to be unchangeable. As shown and preferably, the first named features of the picture, namely, the hair and the like, are made on cardboard attached 90 to the said face plate. The second named features, the eyes, eyelashes, eyebrows, nostrils and lips, are made by paint or color applied directly to the face plate. This makes the main unchangeable features of the picture stand out with 95 respect to the face proper. In any case these several features are made opaque, leaving the face plate transparent where the outline or contour of the face proper is to appear.

On the back plate 16 is depicted the coloring 100 matter 25 of the face. This is located in horizontal projection back of the transparent part 14b in the face plate defining the contour of the face, so as to be disclosed therethrough in proper association with the hair, eyes, eyelashes, eyebrows, nostrils and mouth as if superposed thereon. It is obvious that the normal appearance of the face will be that including the vivid coloring 105 25 on the back plate 16, as shown in Figure 1.

When the band is operated to continuously pass 110

its forward lap between the face plate 14 and the back plate 16, the back plate or rather the coloring 25 thereon, will be revealed when the window 18a is in front of it, but will be obscured and masked 5 when the windowless part of the band is in front of it. In the latter case the white band will occupy the space in the picture otherwise occupied by the coloring 25 on the back plate, which coloring it will mask. On this dead white face, 10 closed through the transparent part 14b of the face plate, appear in proper association the unchangeable features, as the hair, eyes, eyelashes, eyebrows, nostrils and lips, thus giving as in Figure 3 the same face as shown in Figure 1, except 15 that the vivid coloring of Figure 1 will be replaced by the white mask shown in Figure 3.

Any suitable words or slogans designed to set forth the article to be advertised, as in this case 20 a face powder, may be applied to the signboard 20 in the neighborhood of the advertising device proper to associate the two different views of the face with the use of the article advertised in the one case to be contrasted with the use of articles other than that advertised.

25 While in describing an embodiment of the invention I refer to details of construction and to arrangement of parts designed particularly for the specific article advertised as described herein, the invention is not limited thereto, except as 30 may be pointed out in the appended claims.

I claim as my invention:

1. In an advertising device, a transparent face plate, a back plate, a band having a window and being movable in a plane between said back and 35 face plates, opaque means depicting upon said face plate unchangeable features of a picture to be presented, said back plate bearing features of said picture to be changed, said last named fea-

tures being disclosed through the part of the face plate left transparent to superpose the features on the face plate upon the features on the back plate, and means for moving said band to alternately mask and disclose features on said back plate. 80

2. In an advertising device, a transparent face plate, a back plate, a white band having a window and being movable in a plane between said back and face plates, opaque means depicting upon said face plate the hair, eyes, eyelashes, eyebrows, nostrils and lips of the head to be pictured with the part of the plate outlined by the hair to present the contour of the face plate left transparent, a colored contour on the back plate normally visible through the transparent part of the face plate in association with the features depicted on said face plate, and means for moving said band to alternately mask and disclose the colored contour on said back plate. 85

3. In an advertising device, a transparent face plate, a back plate, an endless band having a window and having a lap movable in a plane between said back and face plates, rolls on which said endless band is mounted, opaque means depicting upon said face plate the hair, eyes, eyelashes, eyebrows, nostrils and lips of a head to be pictured with the part of the plate outlined by the hair to present the contour of the face left transparent, a colored contour on the back plate 100 normally visible through the transparent part of the face plate in association with the features depicted on said face plate, and means for driving said rolls to move said band to alternately mask and disclose the colored contour on said 110 back plate. 105
